ATTORNEY

UNITED STATES PATENT OFFICE.

EDWARD GENE, OF CLEVELAND, OHIO.

DESIGN FOR A SEWING-MACHINE CASE.

SPECIFICATION forming part of Design No. 11,969, dated September 28, 1880.

Application filed June 14, 1880. Term of patent 7 years.

To all whom it may concern:

Be it known that I, EDWARD GENE, a citizen of the United States, residing at Cleveland, in the county of Cuyahoga and State of Ohio, have invented and produced a new and original Design for Sewing-Machine Cases, of which the following is a specification, reference being had to the accompanying photograph, forming part thereof.

10 In the photograph is shown a view, in perspective, of a sewing-machine case constructed according to my design.

15 A is the front of the case, provided at its center with a recessed panel, and upon either side of the recessed panel with raised panels $a' a'$. I prefer to make these panels of a different quality of wood from that of which the body of the case is made—as, for example, if the body of the case is made of black walnut.

20 I would make the panels of French walnut.

B represents an end provided with a recessed panel. C is the top, made somewhat longer than the case and adapted to project over the ends B. D D are pieces resting upon the 25 front and back and underneath the top C, being placed at an angle with both the top and

sides. This piece D has the effect of presenting to the eye the case as having an angular appearance.

What I claim is—

1. In a design for a sewing-machine case, the front A, having its central portion provided with a horizontal recessed panel, and its end portions respectively provided with vertical relief-panels, the flat top C, and the inclined piece D, extending between said top and front, substantially as set forth. 30

2. In a design for a sewing-machine case, the front A, having its central portion provided with a horizontal recessed panel, and its end portions respectively provided with vertical relief-panels, the flat top C, the inclined portion D, and the end B, provided with a central recessed panel, substantially as set forth. 40

In testimony whereof I have signed my name to this specification in the presence of two subscribing witnesses. 45

EDWARD GENE.
